UNITED STATES PATENT OFFICE.

CHARLES THOMPSON, OF TORONTO, ONTARIO, CANADA.

CONTACT-TIP FOR CONTACT-FINGERS FOR ELECTRICAL CONTROLLERS AND SWITCHES.

1,330,561.

Specification of Letters Patent. Patented Feb. 10, 1920.

Application filed September 27, 1919. Serial No. 326,807.

To all whom it may concern:

Be it known that I, CHARLES THOMPSON, a subject of the King of Great Britain, of the city of Toronto, county of York, Province of Ontario, Canada, have invented 5 certain new and useful Improvements in Contact-Tips for Contact-Fingers for Electrical Controllers and Switches, of which the following is a specification.

10 My invention relates to improvements in contact tips, and relates more particularly to the type of tip used on contact fingers for electrical controllers and switches, and the principal object of my invention is to provide 15 a contact tip which can be much more accurately and cheaply manufactured than the contact tips with which I am acquainted, so that there will be no possibility of it being impossible to lock the tip to the 20 end of the contact finger. Another object of my invention is to improve the manufacture of this type of tip so that there will be no possibility of the sides of the slot therein being bent or distorted so as to prevent the 25 ready placing of the tip on the contact finger.

In the following specification, I shall describe two embodiments of my invention, and what I claim as new will be pointed 30 out in the claims forming part of this specification.

Figure 1 shows an end elevation of my contact tip showing the same coupled to one end of a contact finger. Fig. 2 is a view 35 similar to Fig. 1, except that certain portions of the contact tip have been removed so as to show the manner in which the contact tip is locked to the end of the contact finger. Fig. 3 is a central longitudinal section through my preferred form of contact tip, and Fig. 4 is a central longitudinal section through a modified form of my contact tip.

In the drawings, like characters of reference 45 refer to the same parts.

My contact tip comprises a plurality of plates, and in the preferred form each of these plates is stamped from metal of the desired gage, at which time the housing slot 50 for the end of the contact fingers is formed, as well as one or more notches, and holes through which the fastening means is passed to hold said plates together. Since each of the said plates is stamped by a die, 55 it will be understood that there will be no variation in the distance of the outer edge

of each notch from the outer edge of each flange, and as the receiving slot in each plate will be of the desired depth, each tip will be positively locked to the end of the 60 contact finger. Enough has been clearly shown to support the statement that there will be no culls in the manufacture of my contact tip, and consequently I obtain a great saving in cost of manufacture. 65

Furthermore, since each plate will be stamped by a die, the operations necessary to manufacture the old type of tip, are not necessary.

By reason of the accuracy with which my 70 contact tip can be made there will be very little, if any, movement of the contact tip on its finger.

It will, of course, be understood that my contact tip may be made of any desired 75 shape of form, and although I show the same in both forms provided with two recesses or pockets, it will be understood that it may be made with only one recess or pocket. 80

The width of the contact tip may vary as desired, and it will be understood that according to my invention said contact tip may be made with one operation from sheet metal which is not too thick. In that case, 85 there will be no necessity to stamp the holes for the fastening means hereinafter referred to specifically, which holds the various plates together in the preferred form of tip. 90

When the contact tip is composed of a plurality of plates, in order to secure them together in accurate relationship, they may be mounted in a suitable hinged form, and then the fastening means positioned and secured in place while the plates are so held. 95

There are a large number of contact fingers on the market, and as these are provided with lugs, I prefer to make my contact tip with recesses or pockets, properly 100 located so that they may be used with the existing contact fingers, though it must be clearly understood that my contact tip may be provided with any suitable interlocking means to co-act with any suitable interlocking means carried by a contact finger. 105

The preferred form of contact tip A is made of a plurality of plates B and B'. Each of these plates is formed by a die, at which time the open slot C is formed therein as well as the holes E. The plates B' are provided with the notches D, when the 110

open slot C is formed therein, and when these plates B' are properly assembled, the said notches form a common recess or pocket D' (see Fig. 3). Through the holes 5 E are passed suitable fastening means such as rivets F, and the same are headed up after any suitable manner.

The manner of making each of the said plates B and B' absolutely insures that each 10 open slot G will align with the other open slots, thus forming a common open slot C' which receives the head G of the contact finger H. The lip I of said contact finger is provided with a lug J which is substantially 15 of the same size as the recess or pocket D'.

The head of the contact finger 4 is the gage for the tip, and, therefore, it will be understood that the distance of the edge 2 of the pocket D' from the end 8 of the slot 20 C' will be substantially the same or very slightly more than the distance from the face 3 of the lug J and the extreme end 9 of the head G, so that when the said tip is placed on said head, the lug J in due course 25 will snap into its corresponding recess.

Because of the manner in which my contact tip is made, the flanges 4 are much thicker than the flanges of the old type of contact tip, and consequently by reason of 30 the disposition of the width of the plates B and B', which is substantially at right angles to the longitudinal axis of the tip, there

will be no possibility of the said flange being bent so as to distort the common slot C'.

In Fig. 4, the plates B'' are shown as 35 clamped between two outer plates 7 and these said outer plates are much thicker than the said plates B''.

What I claim is,

1. As a new article of manufacture, a 40 contact tip comprising a plurality of stamped plates in each of which is stamped an open slot, which, when said plates are assembled, form a common open slot; certain of said plates being provided at the 45 same time when said open slots are formed therein with a notch, which when said certain plates are assembled form a common recess, and means whereby said plates are secured together. 50

2. As a new article of manufacture, a tip made of a plurality of stamped open slotted plates, certain of the interior plates only being each provided with a notch which form a common recess when said plates are 55 assembled, and means for securing said plates together.

3. As a new article of manufacture, a tip made of a plurality of stamped open slotted plates, certain of said plates being adapted 50 to interlock with the head of a contact finger which is embraced by said slotted plates, and means for securing said plates together.

CHARLES THOMPSON.
